US0D1095747S

(12) **United States Design Patent** (10) **Patent No.:** **US D1,095,747 S**
Dishong (45) **Date of Patent:** **** Sep. 30, 2025**

(54) **PROTECTIVE FISHING HOOK AND LURE COVER**

(71) Applicant: **Linda Dishong**, Imler, PA (US)

(72) Inventor: **Linda Dishong**, Imler, PA (US)

(**) Term: **15 Years**

(21) Appl. No.: **29/920,783**

(22) Filed: **Dec. 13, 2023**

FIG. 1 shows a perspective view of a protective fishing hook and lure cover;

FIG. 2 shows a top plan view of the protective fishing hook and lure cover;

FIG. 3 shows a bottom plan view of the protective fishing hook and lure cover;

FIG. 4 shows a right side view of the protective fishing hook and lure cover;

FIG. 5 shows a left side view of the protective fishing hook and lure cover;

FIG. 6 shows a front plan view of the protective fishing hook and lure cover; and,

FIG. 7 shows a rear plan view of the protective fishing hook and lure cover.

The broken lines shown in the figures depict portions of the article that form no part of the claimed design.

1 Claim, 7 Drawing Sheets
